Primary Examiner — Thomas Johannes*Assistant Examiner* — Keith Frank(74) *Attorney, Agent, or Firm* — Nash and Titus, LLC(57) **CLAIM**

The ornamental design for a glass container, as shown and described.

DESCRIPTION

FIG. 1 is a front elevation view of a first embodiment of a glass container showing the new design.

FIG. 2 is a side elevation view of the first embodiment.

FIG. 3 is a side perspective view of the first embodiment.

FIG. 4 is a top view of the first embodiment.

FIG. 5 is another top view of the first embodiment.

FIG. 6 is a bottom view of the first embodiment.

FIG. 7 is another side perspective view of the first embodiment.

FIG. 8 is a front elevation view of a third embodiment of a glass container.

FIG. 9 is a side elevation view of the third embodiment.

FIG. 10 is front perspective view of the third embodiment.

FIG. 11 is a top view of the third embodiment.

FIG. 12 is another top view of the third embodiment.

FIG. 13 is a bottom view of the third embodiment; and,

FIG. 14 is a side perspective view of the third embodiment.
